TELEPHONE SYSTEM

John Wicks, Oak Park, Ill., assignor to Associated Electric Laboratories, Inc., Chicago, Ill., a corporation of Delaware

Application May 3, 1937, Serial No. 140,317

29 Claims. (Cl. 179—21)

The present invention relates to signalling systems and more particularly to automatic switches of the so-called cross bar type for use in setting up connections between the various lines of an automatic telephone system.

It is well known that the method by which a connection is established from one line of a telephone system to any desired second line in the system consists of routing a connection by way of traffic concentration switches, and two or more tandem connected impulse responsive numerical switches which operate automatically to select the desired line and to establish a connection thereto. Various types of numerical switches for performing the functions noted are known to the art. Perhaps the best known and most commonly used switch of this type is the so-called Strowger switch employing a movable wiper mechanism having two directions of movement. The complicated nature of this type of switch has led to considerable research in attempts to secure more simple and less expensive switches capable of performing the same functions. One of the outgrowths of this development is the so-called cross bar type of switch, of which several modifications have been devised. One of the best known and most successful forms of the cross bar switch yet developed is that employing stationary conductors or bars arranged in sets leading to the lines outgoing from the switch and wipers or contacts connected to the incoming trunk line of the switch and arranged selectively to be brought into engagement with the sets of bars, corresponding to the various outgoing lines, by actuating means in the form of relays. The method of selection of a particular line in the outgoing group of lines to which the switch has access is accomplished by control means for the wiper actuating relays, this control means functioning in response to received impulses transmitted from a calling substation to select a particular relay, following which the selected relay is energized to establish a connection between the incoming trunk line to the switch and the selected outgoing line. While the above-described type of switch has met with approval in a few countries, it has not been generally accepted as a substitute for the Strowger type of switch because of certain disadvantages in regard to its constructional and operational features. As an example of these disadvantages there may be cited the fact that the control means, whereby desired ones of the wiper actuating relays are selected, is of a complicated nature and the fact that the connections secured between the wipers

and the bars are not sufficiently positive to insure completely faithful operation of the switch.

It is an object of the present invention, therefore, to provide in a telephone system an improved form of automatic switch of the cross bar type which is of simple and economical and rugged construction and which obviates the disadvantages of conventional switches of this type as pointed out above.

More specifically, it is an object of the invention to provide an automatic switch of the character noted which may readily be substituted for any of the well-known forms of step-by-step numerical switches in an installed system and wherein there is insured positive engagement between the contacts associated with the line incoming to the switch and the contacts associated with any selected outgoing line, the number of relays for actuating the various contact sets is reduced to a minimum, and the control apparatus, whereby a particular line outgoing from the switch is selected, is simple in the extreme.

The improved automatic switch, as described in detail hereinafter, is shown as being embodied in an automatic telephone system of the general character briefly described above and which comprises line switches individual to each of the lines included in the system, groups of first numerical or intermediate selector switches to which the line switches are accessible, and groups of final numerical or connector switches which are accessible to each of the intermediate selector switches. In general, the objects as set forth above are realized in accordance with the present invention by providing as the intermediate and final numerical switches automatic switches each of which comprises a plurality of groups of contacts, each group being arranged in sets including one or more individual contacts, each set being individually connected to the line incoming to the switch, actuating means common to each group of contacts for moving the same from one position to a second position, a plurality of additional groups of contacts, each group of which is arranged in sets individually connected to the lines outgoing from the switch, actuating means common to each of the second-mentioned group of contacts for moving the same from one position to a second position, and control means for selectively energizing the actuating means in accordance with received impulses transmitted to the switch; the contacts of the first-mentioned plurality of groups of contacts being so arranged relative to the contacts of the second-mentioned plurality of groups of contacts that when the contacts of one group of each

plurality of groups are moved to their respective second positions, the one or more individual contacts of a single set included in the moved group of the first-mentioned plurality of groups engage 5 the one or more individual contacts of a single set included in the moved group of the second-mentioned plurality of groups.

More specifically, the actuating means for each group of contact sets comprises a single bar 10 associated with the contacts of the corresponding group and adapted to be moved from one position to a second position by a single operating magnet. In an arrangement for serving one hundred lines, ten vertical bars requiring ten 15 operating magnets hereinafter designated as vertical magnets and ten horizontal bars requiring ten operating magnets hereinafter designated as horizontal magnets must be provided, each of the vertical and horizontal bars being arranged 20 simultaneously to actuate ten contact sets.

The control means included in the automatic switch comprises a single stepping switch of the rotary type having a normal position and a plurality of off-normal positions each of which corresponds to a group of lines in the plurality of 25 lines outgoing from the switch and a particular line in each group. More specifically, the stepping switch includes a plurality of sets of contacts, wipers individually associated with the 30 contact sets, and a motor magnet for causing repeated operations of the switch, to select a desired group of lines and a particular line in the selected group. The motor magnet for actuating the wipers of the switch is under the 35 control of impulse responsive means comprising a line relay, and this means is arranged in different manners depending upon whether the switch is to be used as an intermediate selector unit or a final selector unit. In the first-mentioned case, the control means operates in response to a predetermined series of received impulses to cause the motor magnet to step the wipers of the stepping switch to a position corresponding to the selected group of outgoing lines, 40 following which the motor magnet is automatically conditioned to cause the wipers to continue to be stepped, thereby automatically to test the lines of this group until an idle line in the selected group is found. Following the selection of an 45 idle line in the selected group, means operate to reenergize the motor magnet, thereby to restore the stepping switch to normal. When used as a final selector or connector unit, the control means associated with the stepping switch includes means for causing the wipers of the switch 50 to be returned to normal at the conclusion of the first or tens series of received impulses and following the selection of a desired group of lines, following which the wipers are stepped in 55 accordance with the impulses of the final or units series of received impulses at the rate of one step for each impulse until the wipers stand opposite the position corresponding to the particular called line in the selected group of lines. 60 As will be brought out in greater detail herein- 65 after, the mechanism of the automatic switch as well as the control means associated therewith for procuring the form of operation briefly described above is exceedingly simple in arrangement and reliable in operation.

The novel features believed to be characteristic of the invention are set forth with particularity in the appended claims. The invention itself, however, both as to its organization and method of operation, together with further ob-

jects and advantages thereof, will best be understood by reference to the specification taken in connection with the accompanying drawings, in which Figure 1 illustrates the general structural features of an automatic switch constructed in accordance with the present invention; Fig. 2 illustrates the details of one of the horizontal magnets included in the switch of Fig. 1; Fig. 3 illustrates the details of one of the vertical magnets included in the switch of Fig. 1; Figs. 4 to 6, 10 inclusive, illustrate the three contact positions for the contact springs included in a contact spring assembly associated with the vertical magnet of Fig. 3 and the horizontal magnet of Fig. 4; and Figs. 7 and 8 illustrate a complete 15 telephone system including automatic switches of the form shown in Fig. 1 used both as the intermediate and final selector units.

Referring now more particularly to Fig. 1 of the drawings, the mechanical arrangement of 20 an automatic switch constructed and arranged in accordance with the present invention is illustrated. As shown, the switch mechanism is adapted to be supported on shelves such, for example, as the shelves 13, 14, 15, 16 and 17 extending between and secured to side member 11 of a frame 12. Mounted on each of the enumerated shelves is a horizontal magnet, those for the shelves mentioned being indicated at 18, 19, 20, 21 and 22, respectively. Each of these horizontal magnets includes an armature upon which is mounted the horizontal member or bar for actuating the group of contact sets corresponding to the particular magnet. Thus, the magnets 18 to 22, inclusive, include, respectively, 25 armatures 23, 24, 25, 26 and 27, upon which are mounted, respectively, the actuating bars 28, 29, 30, 31 and 32. Each of these bars is guided in its movement in the vertical plane by guide lugs mounted on the shelf carrying the associated 30 magnet in a manner identical with that shown for the bar 28. The ends of the last-mentioned bar ride in slots provided in the upright portions of lugs 33 and 34, mounted at either end of the shelf 13. Each of the horizontal bars 28 to 45 32, inclusive, in cooperation with its respective associated horizontal magnet comprises means for actuating the contacts of an associated group of contact sets from their respective normal positions to their respective off-normal positions. 50 Thus, the bar 28 has associated therewith a group of contact sets, four of which are indicated at 35, 36, 37 and 38. Each of these contact sets includes one or more individual contacts. If the size of the switch requires that a large 55 number of contact sets be placed under the control of each horizontal bar, two horizontal magnets may be required for actuating each bar, one magnet being positioned at each end of each bar. It will readily be apparent how such additional magnets could be embodied in the structure shown. It will further be apparent that the two magnets associated with each bar could have their respective windings connected in multiple for simultaneous energization.

Mounted on the lower shelf 17 is a group of 65 vertical magnets, five of which are indicated at 39, 40, 41, 42 and 43, which individually include, in the order named, armatures 44, 45, 46, 47 and 48. Each of these armatures is arranged to 70 actuate a vertical bar associated with one group of vertical contact sets and guided in its movement by a pair of brackets projecting outwardly from the shelves 13 and 16. These brackets, comprising the pair for guiding the bar associ- 75

ated with the magnet 39 in its movement, are shown at 64 and 65. The bars associated with the armatures noted are indicated at 49, 50, 51, 52 and 53, respectively, and each thereof carries 5 a plurality of projecting arms individually associated with one of the contact sets of the corresponding group of vertical contact sets. Thus, the bar 49, which is under the control of the magnet 39, carries a plurality of arms, five of 10 which are indicated at 54, 55, 56, 57 and 58, each of which projects inwardly and sidewise from the bar 49 so that, when the bar is pulled downward by the armature 44, all of the contacts included in the associated group of contact sets 15 are moved from their respective normal positions to their respective off-normal positions. The contact sets shown in association with the arms 54 to 58, inclusive, of the vertical bar 49 are indicated at 59, 60, 61, 62 and 63, respectively. 20 Each of the contact sets includes one or more individual contacts.

It will be understood that, when a switch of the above-described form, designed to have access to one hundred outgoing lines, is selectively operated to connect a line incoming thereto to any one of the outgoing lines, one hundred contact sets will be required in each of the plurality of groups of contact sets associated respectively with the horizontal and the vertical bars. This 25 necessarily means that ten vertical bars will be required, each arranged to actuate a group of ten contact sets, and ten horizontal bars will be required, each similarly arranged to actuate a group of ten contact sets. It will further be apparent that the conductors of the incoming line including the trunk and test conductors thereof must necessarily be multiplied between the corresponding contacts of all of the contact sets of one plurality of groups of contact sets. Thus, if the incoming line is connected to the plurality of 30 groups of contact sets associated with the horizontal bars, the conductors thereof must necessarily terminate at each of the contact sets actuated by each of these bars. The outgoing lines, 35 on the other hand, terminate only at individual ones of the opposite contact sets or, in the assumed case, one line will terminate at each of the contact sets 59, 60, 61, 62, 63, etc. associated with the vertical bars.

In order selectively to energize the various 30 vertical and horizontal magnets, there may be provided control means comprising a stepping switch of the rotary type diagrammatically illustrated at 66, which includes two contact sets 67 and 68. The individual contacts of the set 67 are connected to one terminal of a corresponding horizontal magnet, HM1, HM2, etc., and the individual contacts of the set 68 terminate at one terminal of a corresponding vertical magnet, 45 VM1, VM2, etc., thereby to permit the various magnets to be selectively energized. While this control means is described in greater detail hereinafter, it is mentioned at this point in order to facilitate an understanding of the manner in 50 which the switch mechanism operates.

Referring now more particularly to Fig. 2 of the drawings, there are illustrated the details of one of the horizontal magnets such, for example, as the magnet 22 shown in Fig. 1 and of 55 one of the spring assemblies associated with the corresponding horizontal bar 32 and the vertical bar 49. This magnet includes a magnetic core comprising a central leg 69 having a winding 70 wound thereon, a heel piece 71, a side piece 72, 60 and an armature 27. The various contact spring 75

assemblies, which individually comprise one contact of each of a pair of associated horizontal and vertical contact sets, are carried by an extension from the side piece 72. Thus, one of the assemblies in the pair of sets associated with the horizontal bar 32 and the vertical bar 49 comprises 5 springs 74 and 75, mounted on the side piece 72 and insulated from each other by an insulating member 78, and from the assembly screws by additional insulating members 77 as shown. The 10 armature 27 is pivoted at 79 and carries the cross bar 32 for actuating the group of springs including the contact set of which the spring 75 is a part. This cross bar is insulated from the spring 75 by an insulating member 80. Each of 15 the other contact springs associated with each of the horizontal bars is similarly insulated from its associated bar. The upper associated set of contact springs comprising the set, of which the spring 74 forms a part, is under the control of 20 the arm 58 projecting from the vertical bar 49. This arm is insulated from the associated set of contact springs by an insulating member 81. Each of the other contact springs associated with 25 each vertical bar is similarly insulated from the corresponding bar.

Referring now to Fig. 3, there is illustrated the vertical magnet 39 for actuating the vertical bar 49 associated with the contact set including the contact spring 74. This magnet comprises 30 a magnetic core having a central leg 84 having a winding 85 thereon, a heel piece 82, a side piece 83, and an armature 44. This armature is pivoted at 87 and is arranged to actuate its associated vertical bar 49 through a toggle member 35 88. As will be pointed out in greater detail hereinafter, the number of springs included in the assembly of each of the contact sets associated with a vertical bar is dependent upon whether the automatic switch is to be used as an intermediate or final selector unit. If used as an intermediate selector unit, three springs are, as shown, included in each third spring assembly, the third spring 76 being utilized for testing the 40 condition of the outgoing line terminating at the 45 corresponding set of contacts. The remaining two spring assemblies included in each associated pair of contact sets comprise only two contact springs, corresponding to the springs 74 and 75 of the assembly shown. In the event the 50 switch is to be used as a final selector unit, only the contact springs, corresponding to the upper and lower springs of the assembly shown, will be incorporated in each spring assembly, the central spring corresponding to the spring 76 being 55 omitted. If required, each of the horizontal and vertical magnets may be provided with additional armatures or contact springs for the purpose of controlling the operation of the switch. Any conventional manner of embodying such additional springs in the magnet structure may be 60 employed.

In the operation of the switch as thus far described, and when one of the vertical magnets such, for example, as the magnet 39 is selected 65 and energized, the bar 49 carried by the armature 44 thereof is moved downward to actuate the contacts of all of the contact springs associated with this bar and included in the sets 59, 60, 61, 62 and 63, from their respective normal positions to their respective off-normal positions. This operation corresponds to the selection of a particular group of outgoing lines and, as will be pointed out in greater detail hereinafter, the particular vertical magnet which is 75

energized corresponds to a particular number of impulses in a series of impulses received by the switch. In the event the switch is used as an intermediate selector unit, this operation causes the contacts on the springs, corresponding to the springs 74 and 76 and included in all of the sets associated with the vertical bar 49, to make contact, thereby to mark the condition of all of the lines of the selected group in the bank contacts of the rotary stepping switch, whereby the lines in the selected group may be tested. In the event the switch is to be used as a final selector or connector unit, no such testing is required, and this explains the reason why only two contact springs are necessary in each spring assembly embodied in this form of switch. Following the energization of one of the vertical magnets, a selected one of the horizontal magnets such, for example, as the magnet 22, is energized, thereby to actuate all of the contacts in the sets associated with the horizontal bar 32 from their respective normal positions to their respective off-normal positions and to complete a connection between the line incoming to the switch and a particular one of the lines in the selected group of lines outgoing from the switch. Thus, with the vertical magnet 39 and the horizontal magnet 22 energized, only the contacts included in the set of vertical contacts 63 will be in engagement with the contacts of the associated horizontal contact set, the remaining contact sets being disengaged due to the deenergized condition of the other vertical and horizontal magnets.

An understanding of the mode of operation just described is facilitated by considering the sequence of contact spring movements illustrated in Figs. 4, 5 and 6, for the spring assembly 74, 75, 76 associated with the horizontal magnet 22 and the vertical magnet 39. Normally, and with the two magnets noted deenergized, the springs 74, 75 and 76 are in the open contact positions illustrated in Fig. 4. With only the vertical magnet 39 energized, the spring 74 is pushed down so that the contacts on the springs 74 and 76 make contact, but the contacts between the springs 74 and 75 remain disengaged, as shown in Fig. 5. This permits the testing operations noted above to be performed. Thereafter, and when the horizontal magnet 22 is energized, the lower spring 75 is pushed up so that the contact of this spring engages the contact of the spring 74, as shown in Fig. 6. Thus, it will be seen that, with one horizontal magnet energized and one vertical magnet energized, the incoming line to the switch is connected only to a particular one of the outgoing lines.

Referring now more particularly to Figs. 7 and 8, considered together, there is illustrated a telephone system wherein automatic switches of the form just described are used as the impulse responsive, intermediate and final selector switches. In general, the system comprises a plurality of telephones or subscribers' substations, two of which are shown at A and B, adapted to be interconnected by means including their respective subscribers' lines 100 and 100' and switch trains including the aforementioned intermediate and final selector switches. These switch trains, when established, may individually comprise the usual line switch associated with each subscriber's line, an intermediate selector switch accessible to the line switch associated with the subscriber's line, and a final selector switch accessible to the operated selec-

tor switch and having bank contacts in which the called subscriber's line terminates. Thus, in the system shown, the line 100 terminates at a line switch 103, which switch has access to a group of selector switches, one of which is indicated generally at 104. The latter switch in turn has access to groups of final selector or connector switches, each connector switch of each group having its bank contacts multiplied to the bank contacts of the other switches in the same group and connected to serve a corresponding group of subscribers' lines included in the system. Thus, the selector switch 104 has access to connector switches, one of which is indicated generally at 105, in the bank contact sets of which the subscriber's line 100' terminates. It is well known that by this general arrangement any subscriber may by proper manipulation of the impulsive device at his substation establish a connection between his line and any other idle subscriber's line in the system.

Each of the line switches included in the system, such, for example, as the line switch 103, may be of any desired commercial construction, although preferably is of the well-known rotary type having three levels of bank contacts, wipers corresponding to the three levels, a ratchet and pawl mechanism for driving the wipers, an operating magnet for actuating the ratchet and pawl mechanism and control means whereby the operating magnet is energized to operate buzzer fashion when a call is initiated on the line associated with the corresponding line switch and is deenergized when the wipers are rotated into engagement with a set of contacts corresponding to the first idle intermediate selector switch available.

Neglecting for the present the details of the intermediate and final selector switches 104 and 105, respectively, and the control means respectively included therein, the system as described above is entirely conventional in form and its operation is well understood in the art. In brief, when a subscriber such, for example, as the subscriber at the telephone A initiates a call over the line 100 to a second subscriber's telephone such, for example, as the telephone B by lifting his receiver from its hook, the line switch 103 associated with the calling subscriber's line operates to select an idle intermediate selector switch and to condition the same to be responsive to impulses transmitted from the impulsive device at the telephone A. As noted above, each of the intermediate selector switches has access to one or more final selector switches at which any subscriber's line of the system terminates. Thus, if the intermediate selector switch 104, for example, is seized by the line switch 103, it operates in response to the dialing of the first digit at the substation A to select a group of trunk lines extending to the group of final selector switches at which the called line 100' terminates. Following this, the seized intermediate selector switch 104 automatically selects a trunk line leading to an idle final selector switch in the selected group of switches and connects the calling subscriber's line 100 through to seize this idle final selector switch. Thereafter, and in response to the dialing of the second digit, the seized final selector switch selects the group of lines in which the called subscriber's line 100' is included. With the switch train in this condition, and when the final or third digit is dialed, the seized final selector switch selects the particular called line in the selected group of lines 75

and, if this line is idle, establishes a connection between the calling and called lines when the called telephone B is answered.

The system conventionally includes means whereby ringing current and ring-back tone current are automatically transmitted, respectively, to the substations of the called and calling parties in case the called line is idle and upon the final selector switch seizing the called line. 5 Also, in accordance with conventional practice, means are provided whereby, in the event the called line is found busy, the calling line is not connected thereto and busy tone current is transmitted back over the established loop to the calling party to indicate the busy condition of the called line. As will be pointed out in detail hereinafter the arrangement is such that the switch train utilized in establishing the connection is released only when the connection is 10 cleared out at the calling party's substation, the entire switch train being held operated when the called party is the first to hang up.

Each of the intermediate and final selector switches preferably embodies the features of the improved automatic switch illustrated in Figs. 1 to 6, inclusive, although it is noted that the system may only partially comprise switches of this form, the remaining automatic switches being of any well-known step-by-step type wherein 15 pulse responsive means are utilized to control the operation thereof. The selector switches 104 and 105 are, however, of the form illustrated in the above noted figures and the mechanical constructions of the two switches are identical with 20 the exception that the final selector switch 105 includes only two springs in each contact spring assembly whereas the switch 104 includes three contact springs in the third contact spring assembly included in each associated pair of contact sets. Two additional contact spring pairs 25 are associated with each of the horizontal and vertical magnets included in each of the intermediate selector switches and one additional spring pair is associated with each of the horizontal and vertical magnets embodied in each 30 of the final selector switches, these additional springs being used for control purposes in the manner described hereinafter. The switch 104 has access, over one hundred outgoing trunk lines, one of which is shown at 109, to each of 35 one hundred final selector switches and, similarly, each of the final selector switches has access to one hundred subscribers' lines terminating at the contact springs associated with the vertical bars of the switch. In view of the 40 previous description, it will be understood that the springs 263 to 265, inclusive, comprise one contact set forming a part of a group of ten similar contact sets under the control of the horizontal actuating bar associated with the horizontal magnet 260 and that the contact set comprising 45 the springs 241 to 244, inclusive, is one of a group of ten similar contact sets under the control of the vertical actuating bar associated with the vertical magnet 240. Similarly, the horizontal magnet 380 of the final selector switch 105, in cooperation with its associated horizontal bar, controls a group of ten contact spring sets 50 including the set of springs 382, 383 and 384, and the vertical magnet 390 in cooperation with its associated vertical bar controls a group of contact sets including the contact springs 391, 392 and 393. It will further be understood that the contact springs 243, 244 and 265 comprise one 55 contact spring assembly and, similarly, that the

associated springs 242, 264 and 241, 263 comprise the two other assemblies of the associated vertical and horizontal contact sets.

The circuit arrangement of the control means included in the intermediate selector switch 104 is necessarily quite different from that of the control means included in the switch 105. This difference is necessitated by the fact that the switch 104 need only operate in response to one series of received impulses to select a particular group of lines, following which it must operate automatically to select an idle line in the selected group of lines, whereas the switch 105 must be responsive to two series of received impulses to select both the desired group of lines and the particular called line in the selected group. This control means for the switch 104 comprises a stepping switch of the rotary type including three sets of contacts 214, 215 and 216, wipers 207, 208 and 209 for respectively engaging the enumerated sets of contacts, a ratchet and pawl mechanism, not shown, for actuating the wipers 207 to 209, inclusive, a rotary magnet 205 for actuating the ratchet and pawl mechanism, and off-normal springs 160 for causing the stepping switch to be returned to normal when a connection utilizing the selector switch 104 is released. The control means for the automatic switch indicated also includes a plurality of relays 200, 210, 220, 230, and 250, their control and controlled circuits, arranged to operate as described in detail hereinafter to insure the automatic selection of an idle final selector switch in a selected group of such switches in the manner briefly referred to above.

The control means embodied in the final selector switch 105 similarly includes a stepping switch of the rotary type comprising two sets of contacts 317' and 318', wipers 315' and 316' for respectively engaging the two sets of contacts named, a ratchet and pawl mechanism, not shown, for actuating these wipers, a motor magnet 307 for driving the ratchet and pawl mechanism and off-normal springs 309 for causing the magnet 307 to return the stepping switch to normal during the release of a connection in which the automatic switch 105 is involved. This control means also includes a plurality of relays 300, 310, 320, 330, 340, 350, 360, and 370, the control and controlled circuits, which relays in cooperation with the stepping switch are operable in the manner set forth in detail hereinafter to cause the switch 105 to perform the line selecting functions briefly described above. The switch 105 also has associated therewith ringing apparatus, 50 not shown, for transmitting ringing current to a called subscriber's line and ring-back tone current to a calling subscriber's line, and a generator, not shown, for transmitting busy tone current to a calling subscriber's line in the event a particular called line is found busy.

Considering now the detailed operation of the intermediate selector switch 104 during the above described sequence of operations, when this switch is seized by the line switch 103, a circuit 65 is completed for energizing the line relay 200, which circuit extends from ground at the upper winding of the relay by way of this winding, to the conductor 127, the armature 252, the trunk conductor 107, the line switch 103, the line conductor 101, the bridge across the line 100 at the calling substation A, the upper line conductor 102, the line switch 103, the trunk conductor 106, the armature 251, the conductor 126, and the lower winding of the relay 200 to battery. The 70 75

line relay 200 operates in response to its energization over the above-traced circuit to complete, at its armature 202 and associated upper contact 203, a circuit for energizing the slow-to-release hold relay 210, this circuit extending from ground at the restored armature 256, by way of the conductor 120, the armature 202, the contact 203, and through the winding of the hold relay 210 to battery. At its armature 201, the line relay 200 opens a point in the circuit for energizing the slow-to-release relay 220. The hold relay 210, upon operating, applies, at its armature 211, ground to the control conductor 103, thereby to hold the line switch 103 operated and to maintain the calling line 100 marked as busy in the banks of the final selector switches. The application of ground to this conductor completes an obvious circuit for holding the lower winding of the polarized relay 250 energized, thereby to render this relay exceedingly fast to operate when its upper winding is energized. At its armature 212, the hold relay 210, upon operating, prepares a point in the circuit for energizing the relay 220. At its armature 213, the relay 210 prepares a circuit for energizing the motor magnet 205 of the rotary stepping switch. At its armature 213', the hold relay 210 opens a point in a circuit, traced hereinafter, for causing the motor magnet 205 to return the wipers 207 to 209, inclusive, to their respective normal positions following the selection of a trunk line extending to an idle final selector switch in a selected group. With the relays 200 and 210 of the switch 104 operated, the control means included in this switch is conditioned to be responsive to the series of impulses comprising the first digit dialed at the calling substation A.

At the beginning of the first impulse of this digit, when the previously traced circuit for energizing the line relay 200 is interrupted at the impulsive device of the calling substation, this relay restores to complete, at its armature 202 and associated contact 204, the previously prepared circuit for energizing the motor magnet 205, this circuit extending from ground on the restored armature 256 by way of the conductor 120, the armature 202 and associated contact 204, the armature 213, the conductor 119 and the winding of the magnet 205 to battery. Simultaneously, the previously prepared circuit for energizing the relay 220 is completed at the armature 201 of the line relay 200 and the first-mentioned relay, namely, the relay 220, operates to complete, at its armature 221 and the associated contact 222, an obvious circuit for energizing the slow-to-release relay 230. The relay 220, upon operating, also opens, at its armature 224, a point in the circuit, traced hereinafter, for energizing the upper winding of the polarized relay 250. When the relay 230 pulls up, it prepares, at its armature 232, a circuit for energizing any one of the ten vertical magnets of the switch 104 selected by the rotary stepping switch, this circuit being held open at the operated armature 221 until the selection is made. At its armature 231, the relay 230, upon operating, opens a point in an alternative circuit, traced hereinafter, for energizing the winding of the motor magnet 205.

At the beginning of the first pulse of the first dialed digit, when the line relay 200 restores, the previously traced circuit for energizing the motor magnet 205 is completed at the armature 202, and this magnet in cooperation with the

associated ratchet and pawl mechanism, not shown, steps the wipers 207 to 209, inclusive, one step or into engagement with the respective first contacts of the three contact sets 214, 215 and 216. Simultaneously the off-normal springs 160 are closed to prepare a circuit for causing the motor magnet to restore the wipers to their respective normal positions. During each succeeding impulse of the series of impulses comprising the first digit, the line relay 200 alternately operates and restores to cause the motor magnet 205 in cooperation with its associated ratchet and pawl mechanism to step the wipers 207 to 209, inclusive, at the rate of one step for each impulse received by the automatic switch. During such impulsive, the relays 210, 220 and 230, by virtue of their slow-to-release characteristics, remain operated.

Since the outgoing line 109' terminates at a set of contacts under the control of the vertical magnet 240 corresponding to the third contact of the contact set 214, the first digit dialed at the calling substation will necessarily comprise three impulses, so that, at the conclusion of this digit, the wipers 207 to 209, inclusive, stand in their respective third positions with the wiper 207 in engagement with the contact corresponding to the vertical magnet 240. Shortly following the end of the first digit, and with the line relay 200 in its operated position such that the circuit for energizing the relay 220 is interrupted at the armature 201, the last mentioned relay restores to prepare, at its armature 224, a point in the circuit for energizing the upper winding of the polarized relay 250. At its armature 221 and associated lower contact 223, the relay 220, upon restoring, completes a circuit for energizing the vertical magnet 240, this circuit extending from ground on the armature noted, by way of the contact 223, the operated armature 232, the conductor 121, the wiper 207 and its associated third contact, the conductor 113, and the winding of the vertical magnet 240 to battery. This vertical magnet, upon operating, completes, at its armature 245, a locking circuit extending by way of the conductor 114 to ground on the control conductor 108 for holding itself operated independently of the rotary stepping switch. At its armature 246, the magnet 240 prepares a circuit, traced hereinafter, for energizing the motor magnet 205, by way of its self-interrupting contacts 206. The magnet 240 in cooperation with its associated vertical bar also actuates each of the contact springs of all of the contact sets included in the group of ten sets associated therewith from their respective normal positions to their respective off-normal positions. Thus, the contact springs 241, 242 and 243 are pulled down so that the spring 243 connected to the control conductor of the trunk line leading to the final selector switch 105 is connected to the spring 244 leading by way of the test conductor 112 to the first contact in the contact level 215 associated with the wiper 208. It will be understood that each of the remaining nine lines in the group including the line 109', and terminating at the contact sets in the same group as the set 241, 242, 243 have their respective control conductors connected by way of a test conductor corresponding to the conductor 112, to a corresponding contact of the contact level 215. Thus, the switch 104 is automatically conditioned to test the trunks in the selected group of trunks until an idle one thereof is found. As will be seen from a consideration of the final selector switch 105, 75

if any particular final selector switch in the selected group is idle, battery is present on the control conductor corresponding to the conductor 111, whereas if it is busy ground is present on this conductor. Thus, when the switch 105 is idle, the armature 312 of the hold relay 310 is restored and battery is present on the control conductor 111. If, on the other hand, this switch is busy, the armature 312 is operated and ground 10 is present on the conductor 111.

The testing of the lines in the selected group is initiated when the slow-to-release relay 230 falls back shortly after the end of the first dialed digit and following the restoration of the relay 220. 15 When this occurs, the original circuit for energizing the vertical magnet 240 is interrupted at the armature 232 and a circuit is completed, at the armature 231, for energizing the motor magnet 205, by way of its self-interrupting contacts 206, 20 this latter circuit extending from ground on the control conductor 108, by way of the conductor 114, the armature 246, the conductor 116, the armature 253 and associated contact 254, the conductor 115, the armature 231, the conductor 118, 25 and through the self-interrupting contacts 206 and the winding of the motor magnet 205 to battery. It will be observed that the wipers 207 to 209, inclusive, of the stepping switch are not restored to normal but start testing from the 30 position which they occupy at the conclusion of the first digit. Thus, in the case under consideration, the wiper 208 stands in its third position and tests successively the lines corresponding to the contacts including and following the third 35 contact of the contact set 215. In the event the trunk line leading to the third final selector switch of the selected group is idle, the wiper temporarily remains in this position, a circuit being completed at the contacts 243 and 244 immediately 40 the vertical magnet 240 operates for causing the immediate operation of the polarized relay 250 before the motor magnet 205 has had sufficient time in which to operate in response to its energization over the above traced circuit. In the case 45 under consideration, however, it is assumed that the final selector switches in the selected group and corresponding to the fourth to tenth contacts inclusive, of the contact set 215 are busy and that the switch 105 corresponding to the first 50 contact of the set 215 is the first available idle final selector switch. Hence, the motor magnet starts to operate buzzer fashion and in cooperation with its associated ratchet and pawl mechanism drives the wipers 207 to 209, inclusive, over 55 the enumerated contacts until the wiper 208 engages the first contact of the contact set 215, whereupon a circuit is completed for energizing the upper winding of the polarized relay 250, this circuit extending from ground on the control conductor 108 by way of the conductor 128, the upper winding of the relay 250, the conductor 129, the restored armature 257, the restored armature 224, the conductor 123, the wiper 208, the first contact of the contact set 215, and the conductor 112 to 60 battery on the control conductor 111 of the line 109'. The polarized relay 250 immediately operates and interrupts, at its armature 253 and associated contact 254, the previously traced operating circuit for the motor magnet 205. At its 65 armature 258, the relay 250 completes a circuit for energizing the winding of the horizontal magnet 260, this circuit extending from ground by way of the armatures, corresponding to the armature 261, associated with the other horizontal magnets 261, indicated by the dash line 261', the armature

261, the conductor 130, the armature 258, the conductor 124, the wiper 209, and its associated first contact, the conductor 129, and through the winding of the magnet 260 to battery. At its armature 257, the relay 250 interrupts the previously traced circuit for energizing its upper winding but it remains operated by virtue of the energized condition of its lower winding. At its armature 256, this relay further interrupts the operating circuit of the hold relay 210 and opens a 10 point in the original circuit for energizing the motor magnet 205. At its armature 253, the relay 250 prepares a third circuit for energizing the motor magnet 205 to restore the wipers 207 to 209, inclusive, to normal, this latter circuit being 15 held open at the armature 213' until the hold relay 210 restores.

The horizontal magnet 260, upon being energized in the above described manner, operates to complete, at its armature 262, an obvious holding 20 circuit for itself and to interrupt, at its armature 261, a common point in the circuits for energizing the other horizontal magnets. At its contact springs 263, 264, and 265, the magnet 260 connects the trunk line 106' incoming to the switch 25 104 to the selected outgoing trunk line 109'. The last mentioned operation extends the loop from the calling subscriber's substation A to the seized final selector switch 105 and results in the energization of the line relay 300 in the latter switch 30 over a circuit including this loop. This line relay, upon operating, completes, at its armature 301, an obvious circuit for energizing the hold relay 310, which relay operates to apply, at the armature 312 and associated contact 314, ground to the 35 control conductor 111. This ground is extended through the operated contact springs 243 and 265 to the control conductor 108, thereby to maintain energized the operated horizontal and vertical magnets 260 and 240, respectively, independently 40 of the control means included in the intermediate selector switch 104.

As a further consequence of the operation of the polarized relay 250 in the switch 104, the operating circuit for the line relay 200 is interrupted at 45 the armatures 251 and 252. This line relay, upon falling back, at its armature 202 and associated contact 203, interrupts a further point in the previously traced operating circuit for the hold relay 210. Restoration of the line relay 200 also 50 causes the sequential operation of the relays 220 and 230, but these operations are without effect at this time.

When the hold relay 210 restores, shortly after the application of ground to the conductor 108 at 55 the armature 312 of the hold relay 310, it removes, at its armature 211, multiple ground from the control conductor 108. At its armature 213', the hold relay 210 completes a circuit for again energizing the motor magnet 205, this circuit extending from ground on the control conductor 108, by way of the conductor 114, the operated armature 246, the conductor 116, the operated armature 253 and its associated contact 255, the conductor 125, the armature 213', the conductor 117, the off-normal springs 160, the conductor 118, and through the self-interrupting contacts 206 and the winding of the motor magnet 205 to battery. Restoration of the hold relay 210 results in the interruption, at the armature 212, of the circuit 70 over which the relay 220 was reoperated, which relay restores after an interval to cause the restoration of the relay 230, the restoration of the relay 220, due to its slow-to-release characteristic, being subsequent to the return of the wipers 75

207 to 209, inclusive, to normal or home positions in the manner explained below.

The motor magnet 205, upon being energized over the above traced circuit, operates buzzer 5 fashion and in cooperation with its associated ratchet and pawl mechanism drives the wipers 207 to 209, inclusive, to their respective normal or home positions, at which time the off-normal springs 160 open to interrupt the operating circuit of this magnet. Thus, the rotary stepping switch is returned to normal immediately following the seizure of an idle final selector switch in the selected group. It is noted here that the energization of the remaining horizontal magnets during the restoration of the stepping switch to normal is prevented by the operation of the armature 261 before the restoring operation occurs. The polarized relay 250 upon operating prepares a circuit for each of these magnets, but these circuits include a common portion 261' comprising the series connected armatures, corresponding to and including the armature 261. Hence, when any one of the horizontal magnets is energized the energizing circuit for each of the other horizontal magnets is opened independently of the relay 250. With the system in this condition, it will be seen that the connection has been extended to the seized final selector switch, that only the relay 250 and the magnets 240 and 30 260 of the switch 104 are operated, and that the rotary stepping switch in the intermediate selector switch 104 is in its normal position ready for further use.

The operation of the line relay 300 and the hold relay 310 in the seized final selector switch 105 conditions this switch to be responsive to impulses comprising the two final digits dialed at the calling substation A. Thus, the hold relay 310, upon operating, applies, at its armature 315, ground to the conductor 143, to prepare holding circuits for all of the vertical and horizontal magnets included in the switch and for the ring cut-off relay 360 and the relay 370. At its armature 315, the hold relay prepares a circuit for energizing the slow-to-release relay 320, this circuit being held open at the armature 301 and associated contact 302 of the operated line relay 300. At its armature 316, the relay 310 opens a point in the circuit for energizing the magnet 307 by way of the off-normal springs 309 and, at its armature 317 it prepares an impulsive circuit for energizing this magnet independently of the springs 309.

At the beginning of the first impulse of the second digit dialed at the calling substation, the line relay 300 restores, to complete, at its armature 301 and associated contact 302, the above-mentioned circuit for energizing the relay 320 causing this relay to operate and complete, at its armature 321 and associated contact 323, a circuit for energizing the slow-to-release relay 330. The last-mentioned relay, upon operating, completes, at its armature 336 an obvious circuit for energizing the lower winding of the relay 340. Operation of the armature 335 of the relay 330 results in the preparation of a circuit, traced hereinafter, for energizing a selected one of the vertical magnets embodied in the switch. At its armature 337, the relay 330 opens a point in a circuit, traced hereinafter, for causing the motor magnet 307 to restore the wipers 315' and 316' to normal following the seizure of the called line.

When the lower winding of the relay 340 is energized in the above-described manner, this relay 75 operates to complete, at the "X" contacts asso-

ciated with the armature 344, a path for short-circuiting its upper winding, this path extending from ground on the control conductor 111, by way of the conductor 151, the armature 344, the said upper winding, the armature 345, and back to ground at the armature 336. The remaining armatures 341 and 345 remain in their respective restored positions until such time as the above-noted short circuit around the upper winding of the relay 340 is interrupted to permit 10 the two windings of the relay to be energized in series.

Returning again to the operations which occur at the beginning of the first impulse of the second digit, when the relay 300 restores, a circuit is completed for energizing the motor magnet 307, this circuit extending from ground on the armature 304, by way of the contact 306, the armature 317, the conductor 149 and through the winding of the motor magnet 307 to battery. The 20 magnet 307, thereupon and in conjunction with its associated ratchet and pawl mechanism, drives the wipers 315' and 316' into engagement with the first contacts of their respective associated contact sets. When the wipers 315' and 316' of 25 the stepping switch take this first step, the off-normal springs 309 are closed, further to prepare the circuit for causing the motor magnet 307 to restore these wipers to normal. The motor magnet 307 is alternately energized and de-energized 30 in accordance with the impulses of the second digit to step the wipers 315' and 316' over their respective associated contact sets at the rate of one contact for each impulse. In the case under consideration, wherein the called line 100' is in a 35 group corresponding to the second contact of the contact set 317', the second digit will necessarily comprise two impulses, so that, at the conclusion of the digit, the wipers 315' and 316' stand in engagement with their respective associated second 40 contacts. It will be understood that the relays 310, 320, and 330, due to their slow-to-release characteristics, remain operated during such impulsion.

At the conclusion of the second digit, the line 45 relay 300 remains energized for a sufficient period of time to permit the relay 320 to restore. When this occurs, a circuit is completed for energizing the vertical magnet 390 corresponding to the impulses comprising the digit dialed, this circuit 50 extending from ground on the restored armature 321 by way of the contact 322, the operated armature 335, the restored armature 341, the contact 342, the conductor 145, the wiper 315' and its associated second contact, the conductor 156, 55 and through the winding of the magnet 390 to battery. This magnet immediately operates its armatures to complete, at the armature 394, a locking circuit extending from ground on the conductor 143 for holding itself operated. The 60 magnet 390 in cooperation with its associated vertical bar also operates all of the contact springs in the group of contact spring sets comprising the set of springs 391, 392, and 393 from their respective normal positions to their respective off-normal positions.

It will be observed that, simultaneously with the completion of the above-traced circuit for energizing the magnet 390, the operating circuit for the relay 330 is interrupted at the armature 321 and 70 its associated contact 323. This relay restores shortly after the vertical magnet 390 operates to interrupt, at its armature 335, the above-traced original circuit for energizing the vertical magnet noted. As a further consequence of the 75

restoration of the relay 330, a circuit is completed at the armature 331 for energizing the motor magnet 307, to cause the wipers 315' and 316' to be returned to their respective normal positions, this circuit extending from ground on the operated armature 304, by way of the contact 305, the restored armature 331, the conductor 148, the closed off-normal springs 309, and through the self-interrupting contacts 308 and 10 the winding of the magnet 307 to battery. The motor magnet 307 thereupon operates buzzer fashion and, in conjunction with its associated ratchet and pawl mechanism, drives the wipers 315' and 316' until they occupy their respective 15 normal positions, at which time the off-normal springs 309 are opened to interrupt the circuit of the magnet 307.

Simultaneously with the completion of the last-mentioned circuit for energizing the motor magnet 307, the previously traced short circuit for the upper winding of the relay 340 is interrupted at the armature 336, thereby causing the two windings of the relay 340 to be energized in series. The relay 340, thereupon, fully operates 25 to interrupt at its armature 345 a further point in the short-circuiting path for its upper winding and to prepare, at its armature 341 and associated contact 343, a circuit traced hereinafter for energizing a selected one of the horizontal magnets embodied in the switch. Thus, the final selector switch 105 is conditioned to be responsive to the impulses comprising the third or units digit dialed at the calling subscriber's substation A.

35 At the beginning of the first impulse of the third digit, when the line relay 300 again restores, the relay 320 reoperates, and the circuit for energizing the motor magnet 307 independently of its self-interrupting contacts 308 is again completed at the armature 304. It is noted here that both the relays 320 and 330 re-operate at the beginning of the third digit and that the latter relay prepares, at its armature 335, a further point in the above-mentioned circuit for energizing a selected one of the horizontal magnets. When the motor magnet 307 is energized at the beginning of the first pulse, it causes the wipers 315' and 316' to be stepped into engagement with their respective associated first contacts and again closes the off-normal springs 309. The wipers 315' and 316' are thereafter stepped in accordance with the succeeding impulses comprising the third digit at the rate of one point per impulse. In the present instance, wherein the horizontal magnet 380 must necessarily be energized in order to complete the connection to the desired called line 100' and this magnet is associated with the third contact of the contact set 318, the units digit will comprise three impulses so that, at the conclusion thereof, the wipers 315' and 316' stand on their respective associated third contacts. With the wiper 316' in this position, and when the relay 320 restores shortly following the end of the digit, a circuit is completed for energizing the selected horizontal magnet 380, this circuit extending from ground on the armature 321, by way of the contact 322, the operated armature 335, the operated armature 341 and its associated contact 343, the armature 355, the conductor 146, the armature 372, the conductor 147, the wiper 316' and its associated third contact, the conductor 138, and through the winding of the magnet 380 to battery. The horizontal magnet 380, 75 when energized over the above-traced circuit,

operates its armature 381 to complete a locking circuit for itself extending from ground on the conductor 143 and by way of the conductor 155. This magnet, in cooperation with its associated horizontal bar, also operates all of the contact 5 springs in the group of contact spring sets, including the set of springs 382, 383 and 384, from their respective normal positions to their respective off-normal positions, whereby the contacts of the enumerated springs engage the respective 10 contacts of the operated springs 381 to 383, inclusive, thereby to complete a connection between the conductors 133, 134 and 140 of the line incoming to the switch and the conductors 135, 136 and 137, respectively, of the called line. 15

Shortly after the horizontal magnet 380 is energized, and when the slow-to-release relay 330 falls back, the previously traced circuit for energizing the motor magnet 307 by way of the off-normal springs 309 and the self-interrupting contacts 308 20 is again completed, thus causing the motor magnet 307 in cooperation with its associated ratchet and pawl mechanism to drive the wipers 315' and 316' until they stand in their respective normal positions, at which time the off-normal contacts 309 open the circuit for the motor magnet. 25

The sequence of operations which occur following the seizure of the called line by the final selector switch 105 depends upon whether this line is found idle or busy. Thus, at the time the called 30 line 100' is seized by the switch, the slow-to-release relay 330 is still operated so that a circuit is prepared at the armature 331 and its associated contact 333 for energizing the busy relay 350. Now, if the called line is busy, ground is 35 present on the control conductor 131, whereas, if the called line is idle, battery is present on this conductor. Hence, if the line is busy at the time it is seized, the above-noted circuit for energizing the busy relay 350 is completed, this circuit 40 extending from ground on the conductor 137, by way of the springs 393 and 384, the conductor 140, the operated armature 331 and associated contact 333, the conductor 142 and through the winding of the relay 350 to battery. This relay, upon 45 operating, interrupts, at its armature 352 and associated contact 353, a point in the circuit for energizing the lower winding of the relay 370 and prepares, at this same armature and the associated contact 354, an alternative circuit for holding itself operated when the slow-to-release relay 330 restores; the alternative circuit noted extending from ground on the control conductor 111, by way of the operated armature 352 and associated contact 354, the conductor 141, the contact 333, the armature 334, the conductor 142, and through the winding of the busy relay to battery. The busy relay 350, upon operating, also applies, 50 at its armature 351, busy tone current to the loop extending through the operated selector switch 104 and the operated line switch 103 to the calling subscriber's substation to indicate to the calling party thereat the busy condition of the called line. When this occurs, the calling party may, by hanging up, interrupt the loop holding the line relay 65 300 operated, thereby to cause the hold relay 310 to restore. This latter relay, upon restoring its armatures 311 and 312, removes ground from the control conductors 111 and 108 and from the hold conductor 143, whereupon the relays 250 and 350, 70 and the magnets 260, 240, 380 and 390 are de-energized and the switch train leading to the called subscriber's line is released.

It is pointed out that during the release of the final selector switch 105, the line relay 300 upon 75

restoring its armature 304 completes, at the contact 306, a circuit for energizing the motor magnet 307 and at its armature 301 a circuit for energizing the relay 320. Both the magnet 307 and the relay 320 are only energized for a short interval, the circuits noted being interrupted when the hold relay 310 restores its armatures 315 and 317. The relay 320 during the short period when operated completes a circuit for energizing the relay 330 which also operates. The short period of energization of the magnet 307 may be sufficient to cause the wipers 315' and 316' to be stepped to their first off-normal positions, such that the off-normal springs 309 are closed. In order to prevent the stepping switch comprising the wipers noted from remaining in off-normal positions an alternative circuit for energizing the magnet 307 by way of the contacts 308 is provided, this circuit being completed when the relays 310 and 330 are de-energized and extending from ground at the armature 316 by way of the armature 337, the conductor 148, the off-normal springs 309, the self-interrupting contacts 308 and through the winding of the magnet 307 to battery. This circuit is interrupted at the off-normal springs 309 following the return of the stepping switch to its normal position. Thus, a safeguard is provided for preventing the stepping switch from being falsely retained in an off-normal position when the final selector switch 105 is released.

In the event the called line 100' is idle at the time it is seized by the final selector switch 105, battery is present on the control conductor 137 and the busy relay 350 is not energized over the above-traced circuit. Shortly after the seizure of the line, and when the relay 330 restores, a circuit is completed for energizing the lower winding of the relay 370, this circuit extending from battery on the control conductor 137, by way of the operated springs 393 and 384, the conductor 140, the armature 331 and its associated contact 332, the conductor 139, the lower winding of the relay noted, the conductor 144 and the restored armature 352, to ground on the control conductor 111. The relay 370 operates, upon the energization of its lower winding, to complete, at its armature 373, an obvious locking circuit for itself, extending from ground on the conductor 143. At its armature 371, it applies ground to the conductor 140 leading to the control conductor 137, thereby to mark the called line as busy at the contact sets to which it is multipled and, at its armature 372, it opens a point in the previously traced original circuit for energizing the horizontal magnet 380. At its armature 374, the relay 370, upon operating, applies ground to the conductor 148 and, at its armature 375, it applies ground to the ringing machine start conductor 161. At its armatures 377 and 378 the relay 370 completes paths for applying ringing current and ring-back tone current to the loops extending respectively to the called subscriber's substation and the calling subscriber's substation.

Ringing current is conducted to the signal device at the called subscriber's substation B over a path including the armature 377, conductor 153, the lower winding of the ring cut-off relay 360, the conductor 152, the contact 362 and its associated restored armature 361, the conductor 133, the operated springs 382 and 391, the line conductor 135, signal device bridged across the line conductors 135 and 136 at the called substation, the line conductor 136, the operated springs 392 and 383 and the conductor 134 and extending

to ground on the restored armature 364 and its associated contact 365. A portion of this current is by-passed by way of the armature 376, the condenser 162 and the loop extending back to the calling subscriber's substation to the receiver at 5 this substation, thereby to indicate to the calling party that the called telephone is idle. It is noted that the relay 360 is so constructed that it does not operate in response to the energization of its lower winding by the alternating ringing 10 current.

When the called party answers, a direct current path is bridged across the line conductors 135 and 136 at the called substation, thereby to complete a direct current circuit for energizing the 15 lower winding of the ring cutoff relay 360, which circuit is identical with that traced above for the ringing current and extends from battery on the conductor 153 to ground at the armature 364. In response to the energization of its lower winding, the relay 360 partially operates to complete the "X" contacts associated with its armature 367, thereby to cause the energization of its upper winding. When this upper winding is energized, the relay 360 fully operates to interrupt, at its 20 armature 368, the start circuit for the ringing machine and to interrupt, at its armatures 361 and 364 and their respective associated contacts 362 and 365, the application of ringing current 25 and ring-back tone current to the loops extending 30 respectively to the called and calling subscribers' substations. At these last mentioned armatures and their respective associated contacts 363 and 366, the calling line is connected to the called line 35 so that a conversational circuit is completed between the calling telephone A and the called telephone B. It is pointed out that talking battery is supplied to the loop extending to the called subscriber's substation through the windings of the 40 impedance element 395, which windings are connected in series with the exchange battery across the conductors 131 and 132. Similarly, talking battery is supplied to the loop extending to the calling subscriber's substation through the windings of the line relay 300. The system remains 45 in this condition until the connection is cleared out at the calling subscriber's substation.

If the called party hangs up first, nothing occurs, the entire switch train being held in its operated condition by virtue of the fact that the 50 relay 300 is maintained energized over the closed loop extending therefrom to the calling substation, the hold relay 310 is held operated by the line relay 300, and the relays 360 and 370 are locked in their respective operated positions due 55 to the presence of ground on the conductor 143. When, however, the calling party hangs up his receiver to interrupt the circuit holding the line relay 300 energized, this relay restores to open the operating circuit for the hold relay 310. The 60 hold relay, upon restoring its armature 311, removes ground from the conductor 143, thereby to interrupt the holding circuits for the magnets 380 and 390 and the relays 360 and 370. At its armature 312, the hold relay removes direct ground 65 from the control conductor 111. The two relays 360 and 370 in turn restore and the last mentioned thereof removes, at its armature 371, ground from the conductor 140. When the magnets 380 and 390 are de-energized, they restore 70 all of the armatures and contact springs, associated respectively therewith, to their respective normal positions. The relay 370, upon restoring its armature 371 to remove ground from the conductor 140, completely removes ground from the 75

control conductor 111, thereby to interrupt the circuits holding the magnets 240 and 260 and the relay 250 operated. Thus, the selector switch 104 is released. Removal of ground from the 5 control conductor 108 permits the line switch 103 to restore to normal, whereupon the entire switch train utilized in setting up the connection between the substations A and B is released and all of the switches involved therein are ready for 10 further use.

From the foregoing description of the system, it will be apparent that the stepping switch included in each of the automatic selector switches 104 and 105 is operable from a normal position 15 to a plurality of off-normal positions, each of which corresponds to a particular group of trunk lines to which the switch 104 has access and also to a particular trunk line in each group. Thus, when the stepping switch is operated to its first 20 off-normal position such that the wipers 207 to 209, inclusive, stand in engagement with their respective associated third contacts, it is conditioned to select the group of trunk lines which terminate at the contact sets under the control 25 of the vertical magnet 240 and also to select the third trunk line in this group. It follows, therefore, that each of the contacts of the set 214 is associated with a particular group of outgoing trunk lines and that each of the contacts of the 30 set 215 is associated with a particular trunk line in each group.

Following the group selection, as described above, the means comprising the vertical magnet 240, the slow-to-release relay 230 and the motor magnet 205 automatically operates to step the stepping switch to a second position to select a particular trunk line, corresponding to an idle final selector switch, in the selected group of trunk lines. This last mentioned means is under 40 the control of means comprising the polarized relay 250 which renders the motor magnet 205 inoperative to continue to step the wipers 207 to 209, inclusive, in the event the trunk line in the selected group of trunk lines and corresponding 45 to the position of the stepping switch at the conclusion of the group selection, is idle. Immediately upon the completion of the final selection, the means comprising one of the horizontal magnets, such, for example, as the magnet 260, operates, to establish a connection between the line 50 106', incoming to the switch 104, and the selected outgoing line.

It will further be apparent that the stepping switch of the final selector switch 105, while similar to that of the intermediate selector switch 104 in that each off-normal position thereof corresponds to a particular group of subscribers' lines and a particular line in each group, differs therefrom in the manner of its control. This difference resides in the fact that the stepping switch of the final selector switch 105 is repeatedly operated from its normal position to one or more of its off-normal positions to select a particular group of subscribers' lines including the called line and to select the particular called line 65 of the selected group of lines.

While there has been described what is at present considered to be the preferred embodiment of the invention, it will be understood that 70 various modifications may be made therein, and it is contemplated in the appended claims to cover all such modifications as fall within the true spirit and scope of the invention.

I claim:

75 1. An automatic switch comprising two sets of

contacts, actuating means individual to each of said sets of contacts for moving the corresponding set of contacts from one position to a second position, said contact sets being so arranged relative to each other that the corresponding contacts of the respective sets engage only when the contacts of both of said sets are moved to their respective second positions, a stepping switch, impulse responsive means for causing the operation of said stepping switch to predetermined positions, 10 and means including said stepping switch for successively energizing said actuating means.

2. An automatic switch comprising a group of contacts arranged in sets, actuating means common to said group of contacts for moving the 15 same from one position to a second position, a second group of contacts arranged in sets, actuating means common to said second group of contacts for moving the same from one position to a second position, the contacts of said first-named 20 group being so arranged relative to the contacts of said second group that when the contacts of both of said groups are moved to their respective second positions the contacts of a single set included in said first-named group engage the contacts of a single set included in said second group, a stepping switch, impulse responsive means for causing the operation of said stepping switch to predetermined positions, and means including 25 said stepping switch for successively energizing 30 said actuating means.

3. An automatic switch comprising a first group of contacts, actuating means for moving the contacts of said group from one position to a second position, a plurality of groups of contacts, each of said groups of contacts being arranged in sets, actuating means individually associated with each of said plurality of groups of contacts for moving the contacts of the corresponding group from one position to a second 40 position, the contacts of said first group of contacts being so arranged relative to the contacts of said plurality of groups of contacts that when said first-named actuating means and a selected one of said last-named actuating means are energized one set of contacts of said first group engages one set of contacts included in the group of contacts with which said selected one of said actuating means is associated, a stepping switch, impulse responsive means for causing the operation of said stepping switch to predetermined positions, and means including said stepping switch for successively energizing said first-named actuating means and a selected one of said last-named actuating means.

4. An automatic switch comprising a plurality of groups of contacts, actuating means individually associated with each of said groups of contacts for moving the contacts of the corresponding group from one position to a second position, a plurality of additional groups of contacts, actuating means individually associated with each of said last-named groups of contacts, the contacts of each of said groups being arranged in sets and the contacts of said first-named plurality of 60 groups of contacts being so arranged relative to the contacts of said last-named plurality of groups of contacts that when a selected one of said first-named actuating means and a selected one of said last-named actuating means are energized one set of contacts of the contact group associated with said selected one of said first-named actuating means engages one set of contacts of the contact group associated with said selected one of said last-named actuating means.

5. A stepping switch, impulse responsive means for causing the operation of said stepping switch to predetermined positions, and means including said stepping switch for successively energizing a selected one of said first-named actuating means and a selected one of said last-named actuating means.
6. An automatic switch comprising a pair of members, a group of contacts associated with each of said members, each of said groups of contacts being arranged in sets and adapted to be moved by the corresponding member, actuating means comprising a magnet individually associated with said members for moving the corresponding member from one position to a second position, said members being so arranged relative to each other that when both thereof are moved to their respective second positions the contacts of a single set of contacts associated with one of said members engage the contacts of a single set of contacts associated with the other of said members, circuits for energizing said magnets, a stepping switch, impulse responsive means for causing the operation of said stepping switch to predetermined positions, and means including said stepping switch for completing said circuits.
7. An automatic switch comprising a first member, a group of members, a group of contacts associated with each of said members, each of said groups of contacts being arranged in sets and adapted to be moved by the corresponding member, actuating means comprising a magnet individually associated with each of said members for moving the corresponding member from one position to a second position, said first member being so arranged relative to said group of members that when the magnet associated therewith and one of the magnets associated with one of the members of said group of members are energized, the contacts of a single set of contacts of the group associated with said first member engage the contacts of a single set of contacts of the group associated with said one member of said group of members, circuits for energizing said magnets, a stepping switch, impulse responsive means for causing the operation of said stepping switch to predetermined positions, and means including said stepping switch for successively energizing the magnet associated with said first member and a selected one of the magnets individually associated with each of the members of said group of members.
8. In a signalling system, a plurality of lines, an automatic switch having access to said lines, said switch comprising a stepping switch operable to a plurality of positions, each of said positions corresponding to a group of said plurality of lines and a particular line in each group, means including means responsive to a predetermined number of received impulses for operating said stepping switch to one of said positions to select a particular group of lines, and means operative following the selection of said group of lines for operating said stepping switch to a second position to select a particular line in said selected group of lines.
9. In a signalling system, a plurality of lines, an automatic switch having access to said lines, said automatic switch comprising a stepping switch including a plurality of sets of contacts and wipers individually associated with said contact sets, each contact of one of said sets being associated with a group of said plurality of lines and each contact of a second set being associated with a particular line in each of said group of lines, a motor magnet for driving said wipers, means for energizing said motor magnet in accordance with the impulses of a predetermined series of received impulses to drive said wipers until the wiper associated with said one contact set engages the contact associated with the one group of lines corresponding to the impulses of said series of impulses, and means for thereafter energizing said motor magnet to drive said wipers until the wiper associated with said second contact set engages the contact associated with a particular desired line in said one group of lines.
10. In a signalling system, a plurality of lines, an automatic switch having access to said lines, an incoming line to said switch, said switch comprising a stepping switch operable to a plurality of positions, each of said positions corresponding to a group of said plurality of lines and a particular line in each group, means including means responsive to a predetermined series of received impulses for operating said stepping switch to one of said positions to select a particular group of lines, means operative following the selection of said particular group of lines for operating said stepping switch to a second position to select a particular line in said selected group of lines, and means automatically operative following the selection of said particular line for establishing a connection between said incoming line and said particular line.
11. In a signalling system, a plurality of lines, an automatic switch having access to said lines, an incoming line to said switch, said automatic switch comprising a stepping switch having a plurality of sets of contacts and wipers individually associated with said contact sets, each contact of one of said sets being associated with a group of said plurality of lines and each contact of a second set being associated with a particular line in each of said groups of lines, a motor magnet for driving said wipers, means for energizing said motor magnet in accordance with a predetermined series of received impulses to drive said wipers until the wiper associated with said one set engages the contact associated with the one group of lines corresponding to the impulses of said series of impulses, means for thereafter energizing said motor magnet to drive said wipers until the wiper associated with said second contact set engages a contact associated with a particular line of said one group of lines there-

- by to select said particular line, and means responsive to the selection of said particular line for establishing a connection between said incoming line and said particular line.
- 5 12. In a signalling system, an automatic switch comprising a plurality of groups of contact sets, a plurality of additional groups of contact sets, actuating means individually associated with each of said groups of contact sets for moving 10 the contacts of the contact sets included in the corresponding group from one position to a second position, a plurality of lines individual ones of which terminate at individual contact sets of said second-named plurality of groups of contact sets, an incoming line to said switch, said incoming line terminating at each of the contact sets of said first-named plurality of groups of contact sets, a stepping switch included in said automatic switch and operable to a plurality of 20 positions, each of said positions corresponding to one of the actuating means associated with one of the groups of contact sets included in said first-named plurality of groups of contact sets and to one of the actuating means associated 25 with one of the groups of contact sets included in said second-named plurality of groups of contact sets, means including means responsive to a predetermined series of received impulses for operating said stepping switch to one of said positions, the actuating means for moving the contacts included in one group of said first-named plurality of groups and corresponding to said position being energized when said switch is operated to said one position, whereby a particular 30 group of said plurality of lines is selected, means operative following the selection of said particular group for operating said switch to a second position, the actuating means for moving the contacts included in one group of said second-named plurality of groups and corresponding to said second position being energized to connect said incoming line to a particular line in said selected group of lines when said switch is operated to said second position.
- 45 13. In a signalling system, a plurality of lines, an automatic switch having access to said lines, said switch comprising a stepping switch having a normal position and being operable to a plurality of off-normal positions, each of said off-normal positions corresponding to a group of said plurality of lines and to a particular line in each group, means including means responsive to a predetermined series of received impulses for operating said stepping switch to one 50 of said off-normal positions to select a particular group of lines, means operative following the selection of said group of lines for operating said stepping switch to a second off-normal position to select a particular line in said selected group of lines, and means automatically operative immediately following the selection of said particular line for restoring said stepping switch to normal.
- 55 14. In a signalling system, a plurality of lines, an automatic switch having access to said lines, an incoming line to said switch, said switch comprising a stepping switch having a normal position and a plurality of off-normal positions, each of said off-normal positions corresponding to a 60 group of said plurality of lines and to a particular line in each group, means including means responsive to a predetermined series of received impulses for operating said stepping switch to one of said off-normal positions to select a particular group of lines, means operative following the selection of said particular group of lines for operating said stepping switch to a second off-normal position to select a particular line in said selected group of lines, and means automatically operative immediately following the selection of said particular line for restoring said stepping switch to normal.
- 65 15. In a telephone system a plurality of selector switches, an additional selector switch having access to each of said plurality of selector switches, said additional switch comprising a stepping switch having a plurality of positions, each of said positions corresponding to a group of said plurality of selector switches and to a particular switch in each group, means including means responsive to a predetermined series of received impulses for operating said stepping switch to one 70 of said positions to select a particular group of said plurality of selector switches, and means for causing said switch to continue operating from position to position until it stands in a position corresponding to an idle switch in said selected group.
- 75 16. In a telephone system a plurality of selector switches, an additional selector switch having access to each of said plurality of selector switches, said additional switch comprising a stepping switch having a plurality of positions, each of said positions corresponding to a group of said plurality of selector switches and to a particular switch in each group, means including means responsive to a predetermined series of received impulses for operating said stepping switch to one 80 of said positions to select a particular group of said plurality of selector switches, and means for causing said switch to continue operating from position to position until it stands in a position corresponding to an idle switch in said selected group, and means for rendering said last-named means inoperative in the event the selector switch in said selected group of selector switches and corresponding to said one position of said stepping switch is idle.
- 85 17. In a telephone system, a plurality of selector switches, an additional selector switch having access to each of said plurality of switches, an incoming line to said additional switch, said additional switch comprising a stepping switch having a plurality of positions, each of said positions corresponding to a group of said plurality of selector switches and to a particular switch in each group, means including means responsive to a 90 predetermined series of received impulses for operating said stepping switch to one of said positions to select a particular group of said plurality of selector switches, means for causing said stepping switch to continue operating from position to position until it stands in a position corresponding to an idle selector switch in said selected group, means for rendering said last-named means inoperative in the event the selector switch in said selected group and corresponding to said one position of said stepping switch is idle, and means operative when an idle selector switch in said selected group is found for connecting said incoming line through to said idle selector switch.
- 95 18. In a telephone system, a plurality of selector switches, an additional selector switch having access to each of said plurality of switches, an incoming line to said additional switch, said additional switch comprising a stepping switch hav-

ing a normal position and a plurality of off-normal positions, each of said off-normal positions corresponding to a group of said plurality of selector switches and to a particular switch in each group, means including means responsive to a series of received impulses for operating said stepping switch to one of said off-normal positions to select a particular group of said plurality of selector switches, means for causing 5 said stepping switch to continue operating from position to position until it stands in an off-normal position corresponding to an idle selector switch in said selected group, means for rendering said last-named means inoperative in the event the selector switch in said selected group and corresponding to said one position of said stepping switch is idle, means operative when an 10 idle selector switch in said selected group is found for connecting said incoming line through 15 to said idle selector switch, and means operative when said idle selector switch is found for restoring said stepping switch to its normal position 20

19. In a signalling system, a plurality of lines, 25 an automatic switch having access to said lines, said switch comprising a stepping switch having a normal position and a plurality of off-normal positions, each of said off-normal positions corresponding to a group of said lines and to a particular line in each group, and means including 30 means responsive to successive series of received impulses for repeatedly operating said stepping switch between its normal position and one or more of its off-normal positions to select a particular group of lines and a particular line in the 35 selected group of lines.

20. In a signalling system, a plurality of lines, 40 an automatic switch having access to said lines, said switch comprising a stepping switch having a normal position and a plurality of off-normal positions, each of said off-normal positions corresponding to a group of said lines and to a particular line in each group, and means including 45 means responsive to successive series of received impulses for repeatedly operating said stepping switch between its normal position and one or more of its off-normal positions to select a particular group of lines and a particular line in the selected group of lines, said last-named means being operative immediately following the selection 50 of said particular line to restore said stepping switch to its normal position.

21. In a signalling system, a plurality of lines, 55 an automatic switch having access to said lines, said switch comprising a stepping switch having a normal position and a plurality of off-normal positions, each of said off-normal positions corresponding to a group of said plurality of lines and to a particular line in each group, means including 60 means responsive to one predetermined series of received impulses for operating said stepping switch to one of said off-normal positions to select a particular group of said lines, and means operative following the selection of said group of lines for returning said stepping 65 switch to its normal position, said first-named means being thereafter responsive to a second predetermined series of impulses to reoperate said stepping switch to one of its off-normal positions to select a particular line in said selected 70 group of lines.

22. In a signalling system a plurality of lines, 75 an automatic switch having access to said lines, said switch comprising a stepping switch having a normal position and a plurality of off-normal

positions, each of said off-normal positions corresponding to a group of said plurality of lines and to a particular line in each group, means including means responsive to one predetermined series of received impulses for operating said stepping switch to one of said off-normal positions to select a particular group of said lines, means operative following the selection of said group of lines for returning said stepping switch to its normal position, said first-named 10 means being thereafter responsive to a second predetermined series of impulses to reoperate said stepping switch to one of its off-normal positions thereby to select a particular line in said selected group of lines, and means automatically 15 operative immediately following the selection of said line for again restoring said stepping switch to normal.

23. An automatic switch comprising a plurality of contact sets, common means for moving 20 said plurality of contact sets from one position to a second position, a first additional contact set, means for moving said first additional contact set from one position to a second position, a second additional contact set, means for moving 25 said second additional contact set from one position to a second position, said contact sets being so arranged relative to each other that one contact set of said plurality of contact sets engages said first additional contact set when 30 both of these contact sets are moved to their respective second positions and that another contact set of said plurality of contact sets engages said second additional contact set when both of these contact sets are moved to their respective 35 second positions, and means operable in response to the movements of said plurality of contacts and one of said additional contact sets to their respective second positions for preventing the movement of the other of said additional contact sets to its second position.

24. An automatic switch comprising a plurality of contact sets, common means operative to move 40 said plurality of contact sets from one position to a second position, a first additional contact set, a first additional means operative to move said first additional contact set from one position to a second position, a second additional contact set, a second additional means operative to move said second additional contact 45 set from one position to a second position, said contact sets being so arranged relative to each other that one contact set of said plurality of contact sets engages said first additional contact set when both of these contact sets are moved to their respective second positions and that another contact set of said plurality of contact sets engages 50 said second additional contact set when both of these contact sets are moved to their respective second positions, and means operable after the operation of said common means and in response to the operation of one of said additional means for preventing the operation of the other of said additional means.

25. An automatic switch comprising a plurality 55 of contact sets, common means operative to move said plurality of contact sets from one position to a second position, a first additional contact set, means including a first magnet operative to move said first additional contact set from one position to a second position, a second additional contact set, means including a second magnet operative to move said second additional contact set from one position to a second position, said contact sets being so arranged relative 60

- to each other that one contact set of said plurality of contact sets engages the first additional contact set when both of these contact sets are moved to their respective second positions and 5 that another contact set of said plurality of contact sets engages said second additional contact set when both of these contact sets are moved to their respective second positions, circuits for energizing said magnets, and means operable 10 after the operation of said common means and in response to the operation of one of said magnets for controlling the energizing circuit of the other of said magnets to prevent the operation thereof.
- 15 26. An automatic switch comprising a plurality of contact sets, common means operative to move said plurality of contact sets from one position to a second position, a first additional contact set, means including a first magnet operative 20 to move said first additional contact set from one position to a second position, a second additional contact set, means including a second magnet operative to move said second additional contact set from one position to a second 25 position, said contact sets being so arranged relative to each other that one contact set of said plurality of contact sets engages the first additional contact set when both of these contact sets are moved to their respective second positions 30 and that another contact set of said plurality of contact sets engages said second additional contact set when both of these contact sets are moved to their respective second positions, circuits for energizing said magnets, and means operable 35 after the operation of said common means and in response to the operation of one of said magnets for interrupting the energizing circuit of the other of said magnets to prevent the operation thereof.
- 40 27. An automatic switch comprising a plurality of contact sets, common means operative to move said plurality of contact sets from one position to a second position, a first additional contact set, a first additional means operative to move said first additional contact set from one position to a second position, a second additional contact set, a second additional means operative to move said second additional contact set from one position to a second position, said contact 45 sets being so arranged relative to each other that one contact set of said plurality of contact sets engages said first additional contact set when both of these contact sets are moved to their respective second positions and that another contact set of said plurality of contact sets engages said second additional contact set when both of these contact sets are moved to their respective second positions, a stepping switch, impulse responsive means for causing the operation 50 of said stepping switch to predetermined positions, means including said stepping switch for successively operating said common means and a selected one of said additional means, and 55 means responsive to the operation of said selected one of said additional means for preventing the operation of the other of said additional means.
28. In a signalling system, an automatic switch 5 including a group of contact sets, an incoming line connected to each contact set of said group, a plurality of additional contact sets, outgoing lines individually connected to said additional contact sets, common actuating means 10 operative to move the contact sets of said group from one position to a second position, actuating means individually associated with each of said additional contact sets for moving the corresponding additional contact set from one position to a second position, said contact sets being so arranged relative to each other that one contact set of said group engages a corresponding one of said additional contact sets when both of these contact sets are moved to their respective 20 second positions, impulse responsive means for operating said common actuating means, testing means responsive to the operation of said common actuating means for selecting an idle one of said outgoing lines, and means responsive to the selection of an idle one of said outgoing lines by said testing means for operating said actuating means individually associated with the one of said additional contact sets connected to the selected outgoing line. 30
29. In a signalling system, an automatic switch including a group of movable contact sets, an incoming line connected to each contact set of said group, a plurality of additional movable contact sets, outgoing lines individually connected to said additional contact sets, test contact sets 35 individually associated with said additional contact sets, testing circuits individually connected to said test contact sets, common actuating means operative to move the contact sets of said group from one position to a second position, actuating means individually associated with each of said additional contact sets for moving the corresponding additional contact set from one position to a second position, said contact 40 sets being so arranged relative to each other that the contact sets of said group engage said test contact sets individually associated therewith when the contact sets of said group are moved to their second positions and that one contact set of said group engages one of said additional contact sets when both of these contact sets are moved to their respective second positions, impulse responsive means for operating said common actuating means, testing means including 45 said testing circuits for selecting an idle one of said outgoing lines, and means responsive to the selection of an idle one of said outgoing lines by said testing means for operating said actuating means individually associated with the one of said additional contact sets connected to the selected idle outgoing line. 50
